UNITED STATES PATENT OFFICE.

PETER F. MURPHY, OF MILWAUKEE, WISCONSIN.

WRAPPING-MACHINE.

1,266,705.

Specification of Letters Patent. Patented May 21, 1918.

Application filed August 4, 1913. Serial No. 782,778.

To all whom it may concern:

Be it known that I, PETER F. MURPHY, a citizen of the United States, residing at Milwaukee, in the county of Milwaukee and State of Wisconsin, have invented certain new and useful Improvements in Wrapping-Machines, of which the following is a specification, reference being had to the accompanying drawing, forming a part thereof.

10 This invention relates more particularly to machines for wrapping articles or substances of varying size and shape and of varying solidity or compressibility, such as bread.

15 Its main objects are to facilitate wrapping such articles or substances; to fold the wrapper smoothly over the tops, sides and ends of the packages so that the edges of the wrappers will all be lapped on the bottoms or one side of the packages; to avoid unnecessary handling and consequent contamination of the articles or substances to be wrapped; to tightly inclose and seal the articles or substances wrapped; and generally to simplify and improve the construction and operation of machines of this class, particularly for the specific purpose above stated.

20 It consists in the construction, arrangement and combination of parts as herein-after particularly described and pointed out in the following claims.

25 In the accompanying drawing like characters designate the same parts in the several figures.

Figure 1 is a vertical longitudinal section on the line 1—1, Figs. 5 and 6, of a wrapping machine embodying the invention and designed particularly for wrapping bread, 40 the outer ends of the feed and discharge conveyers being broken away and shown below their inner ends; Fig. 2 is a plan view of the machine; Fig. 3 is a cross section on the line 3—3, Fig. 1, showing one of the adjustable wrapper supports, and the adjustable back stop plate with associated parts; Fig. 4 is a side elevation of the machine as viewed from the left relative to Figs. 5 and 6; Fig. 5 is an end elevation 45 of the machine as viewed from the left relative to Figs. 1 and 2; Fig. 6 is a vertical cross section of the machine on the line 6—6, Figs. 1 and 2; Figs. 7 to 13 inclusive are detail views on an enlarged scale illustrating the operation of the folding mech-

anism and the peculiar manner of folding the wrapper, Fig. 7 being a side elevation of the plunger and end folders with a loaf of bread and a wrapper just before the folding of the wrapper by the end folders, and Fig. 9 showing the end folders turned into the vertical positions which they occupy when the loaf is carried upwardly between them by the plunger.

Although with little or no change the machine may be used or adapted to be used for wrapping other articles, it is shown and will be described as it is constructed and operates for wrapping bread.

The machine comprises generally wrapper folding mechanism, a conveyer for feeding the loaves to be wrapped to the folding mechanism, a discharge conveyer upon which the wrapped loaves are delivered from the folding mechanism, wrapper supporting, guiding, feeding and cutting devices, and means for sealing the wrappers on the bottoms of the loaves.

The folding mechanism consists of vertically disposed parallel side folders and guides 1 and 2, end folders 3, a vertically reciprocating plunger 4, movable up and down between the folders, a reciprocating side tucker 5, located above and movable transversely to the side folders, end tuckers 6, and a reciprocating pusher 7, located above the side tucker and movable parallel therewith and transversely to the side folders.

The side folder and guide 1, comprising a plain smooth-faced metal plate, is fastened stationarily at its upper edge to the top plate 8 of the machine frame, and the side folder and guide 2, comprising a similar plate, is adjustably fastened to the frame parallel with the folder and guide 1, by bolts 9, passing through longitudinal slots 10 in said plate 8, so that the plate 2 may be shifted toward and from the opposing stationary plate 1, for wrapping loaves of different widths. To facilitate its adjustment the plate 2 is provided, as shown in Figs. 1 and 5, with a handle 11. To guide the loaves, which vary more or less in shape, size and solidity or compressibility, without mutilation or injury between the folders and to evenly distribute the pressure and pull upon the wrappers carried with the loaves by the plunger upwardly between the folders, the side folders and guides are

provided with outwardly yielding sections 12, which are hinged or pivoted adjacent to their upper edges to the upper fixed sections of the folders and guides adjacent to 5 their lower edges. The sections 12 are formed along their upper and lower edges with outwardly projecting flanges, the lower flanges being rounded or beveled to avoid sharp corners, and the upper flanges 10 serving as stops to limit the outward movement of the sections, which normally hang in the planes of the upper fixed sections, as shown in Fig. 1.

The pivoted end folders 3 each consist of 15 a head 13 and detachable plate 14, provided as shown in Fig. 7, with lugs 15 and 16, fitting openings or recesses in the head, and with a threaded stud 17 and a thumb nut 18 for detachably fastening it to the head. 20 Each head 13 is formed or provided on the outer side with arms 19 which are pivotally and slidably mounted on rods 20 passing transversely through longitudinal slots 21 in the upper fixed sections of the side folders and guides 1 and 2. The heads 13 are formed or provided with counterweights 22, which tend to hold the end folders in the positions in which they are shown in Figs. 6 and 7, against stops 23 projecting inwardly 25 from one of the side folders. The pivot rods 20 are fastened at one end in blocks or heads 24, slidably mounted on bracket bearings 25 on the outer side of the upper fixed section of the side folder 1, as shown in 30 Figs. 1 and 6. These blocks or heads are movable toward and from each other, and are connected by a right and left adjusting screw 26, by which the end folders may be simultaneously shifted toward or from each 35 other for wrapping loaves of different 40 lengths.

The plunger 4 is removably mounted on the upper end of a reciprocating bar 27, which is guided in vertical ways 28, attached as shown in Figs. 1 and 6, to cross pieces of the machine frame. The plunger is moved up and down between the folders by a lever 29 connected between its ends as shown in Fig. 1, by a rod 30, with an eccentric 50 31 on a transverse shaft 32. The plunger is limited in its downward movement by engagement with a stop 33 at the upper end of the ways 28, as shown in Fig. 1, and the inner end of the lever 29 plays in a vertical slot in the plunger bar 27, thereby causing the plunger to dwell in its lower and initial or normal position, against the stop 33.

A feed shelf or support 34, of sufficient 60 width to carry a single load, is attached to the frame substantially at the level of the plunger in its initial position, and on the side of this shelf next to the path of the plunger, a vertically reciprocating gate 35 65 is guided in ways 36 on a cross member of

the frame, as shown in Figs. 1 and 6. The gate is lifted into operative position above the shelf 34 by springs 37, its upward movement being limited by stops 38 engaging said cross member. In its downward movement the plunger 4, by engagement with a lug 39, carries the gate downward with it into inoperative position below said shelf, as shown in Fig. 1.

To prevent the loaf resting on the shelf 34 75 from being carried upward out of place by the upward movement of the loaf on the plunger and the gate 35, which moves upwardly with the plunger, a vertically movable guard 40 extends over the shelf 34 and is 80 guided by downwardly projecting parallel arms 41 at its ends in bearings on the frame on opposite sides of the path of the plunger. The guard is moved downwardly into operative position to confine a loaf in place on the shelf 34, when the plunger is lifted with a loaf, by springs 42 connecting the arms 41 with a cross piece of the frame, and it is moved upwardly into inoperative position when the plunger descends to its initial position so as to permit the free passage of a loaf from the shelf to the plunger, by levers 43 fulcrumed between their ends on the guideways 36 or other stationary parts of the frame and connected at their outer ends 95 by pins and slots with the arms 41 of the guard, as shown in Fig. 6.

The inwardly projecting arms of the levers 43 are engaged by pins or lugs 44 on the gate, so that when the gate is carried 100 with the plunger downward into its normal position below the shelf 34, the guard is elevated to permit the free passage of a loaf underneath it.

The side tucker 5, consisting of a flat plate 105 extending across an opening in the top or bed plate 8 and guided in parallel ways 45 at the sides of said opening, is connected by a rod 46 with the upper end of a lever 47, which is fulcrumed between its ends on a 110 cross rod 48 and is provided between its fulcrum and its upper end with a roller 49 in the path of a cam 50 on the shaft 32. A spring 51 connecting the lower end of the lever 47 with the frame, withdraws the 115 tucker 5 after its advance by the cam 50, its backward movement being limited by an adjustable stop screw 52, with which the upper arm of the lever 47 engages.

The end tuckers 6, which are located just 120 above and are movable between and lengthwise of the side folders and guides 1 and 2, are detachably fastened to the inner ends of levers 53, which are vertically fulcrumed between their ends to the under side of the 125 bed or top plate 8 on opposite sides of the opening therein, and are provided at their outer ends with rollers 54 engaging peripheral grooves of cams 55 on the shaft 32, as shown in Figs. 2, 5 and 6. The bed or top 130

plate 8 on which the end tuckers 6 rest and are guided, is formed with curved slots, as indicated by dotted lines on Fig. 2, and as shown in Fig. 6, for the passage therethrough of upwardly projecting bosses to which the tuckers are fastened at the inner ends of said levers.

The pusher 7 consists of a plate detachably fastened to a head 56 on the inner end 10 of a sliding rod 57, having bearings on the frame and connected with the upper end of a lever 58 fulcrumed on the rod 48. This lever is provided between its fulcrum and upper end with a roller 59 in the path of a cam 60 on the shaft 32, said cam being arranged to advance the pusher from its initial or normal position above and approximately in line with the side folder and guide 2 across the space between it and the opposing side folder and guide 1. A spring 61 connecting the lower end of said lever 58 with a part of the frame, acts in opposition to said cam to retract the pusher to its initial position, its backward movement 15 being adjustably limited by a stop screw 62 threaded in a cross piece of the frame.

A metal plate 63 for heating and sealing the wrappers on the bottoms of the loaves, is mounted on the frame of the machine next 20 to the stationary side folder and guide 1, approximately in the plane of the bed or top plate 8 and of the side tucker 5. This plate is heated to the required temperature for sealing the wrappers, for which paraffined or waxed paper is used, by an electric heater 64, attached to the under side of the plate.

A vertically reciprocating discharge gate 65, which in its normal position, as shown 25 in Fig. 1, constitutes an upward continuation of the side folder and guide 1, is attached to a rocker frame 66, which is pivotally mounted on a cross shaft 67, supported at its ends in standards 68, extending upwardly from the bed or top plate 8. An arm 69 extending downwardly from the outer pivoted end of the frame 66 is connected by an adjustable link 70 with the upper end of a lever 71, fulcrumed between 30 its ends on the rod 48 and provided with a roller 72 in the path of a cam 73 on the shaft 32, said cam operating to intermittently lift the gate 65 just before each advance movement of the pusher 7. A spring 35 74, connecting the lower end of said lever 71 with the frame, holds the roller 72 in engagement with the cam 73 and operates to return the gate 65 to its normal position after it has been lifted by said cam.

An upwardly yielding presser plate 75 is 40 carried by the rocker frame 66 over the sealing plate 63. The plate 75 is provided with upwardly projecting stems 76 passing loosely through sleeves 77, which are threaded and adjustable vertically in the frame

66. Springs 78 are interposed between the plate 75 and the lower ends of the sleeves 77, and the stems 76 are confined in the sleeves 77 by wing nuts 79 threaded on said stems and bearing normally against the upper ends of said sleeves. By means of the sleeves 77 the distance of the plate 75 in its normal position from the plate 63 may be adjusted for loaves of different heights, and by means of the sleeves 77 and the nuts 79 the tension of the springs 78 is adjusted to exert the desired pressure upon the loaves for sealing their wrappers. 70

Parallel end plates or guides 80, are supported above and transversely to the side 80 folders and guides 1 and 2, by brackets 81, which are attached to the blocks or heads 24 and adjustable therewith toward and from each other by the screw 26.

As shown in Figs. 1 and 4, the feed conveyor consists of an endless belt 82, mounted on rollers 83 and 84 and supported on the upper side, which travels toward the shelf 34, on a plate 85, attached to the under side of longitudinal angle bars 86 in the 90 plane of the shelf 34. The discharge conveyor, which is located directly above the feed conveyor, consists like the feed conveyor, of an endless belt 87, of canvas or other suitable material, mounted on rollers 95 88 and 89, the upper side of the belt, which travels away from the sealing plate 63, being supported substantially in the plane of said plate by a plate 90, attached to the upper sides of longitudinal angle bars 91. The 100 feed belt 82 is driven, as shown in Figs. 2 and 4, by a link belt 92 connecting a cone sprocket wheel 93 on the shaft of the roller 83, with a sprocket wheel 94 on the cam shaft 32. The discharge belt 87 is driven, as 105 shown in Figs. 2 and 4, by a crossed belt 95 connecting a grooved pulley 96 on the shaft of the roller 88 with a grooved pulley 97 on the shaft of the roller 83.

For bringing the loaves into alignment 110 endwise on the belt 82 and depositing them in proper position on the shelf 34 and plunger 4, the feed conveyor is provided with longitudinal guides 98, which are attached at their outer ends to the bars 86 and at their 115 inner ends to posts 99 mounted on a right and left screw shaft 100 and adjustable simultaneously toward or from each other transversely to said belt, as shown in Figs. 1 and 6. This screw shaft is supported and confined endwise in bearings provided therefor in a cross member of the frame below the shelf 34, and is provided at one end as shown in Fig. 6, with a hand wheel or head for turning it. 120

On the opposite side of the path of the plunger from the shelf 34, a back stop and guide plate 101 is pivotally connected adjacent to its upper edge with an arch 102, mounted on a cross bar 103, supported on 130

and adjustable lengthwise of the bars 86, as shown in Figs. 1 and 3. The cross bar 103 is secured in adjusted position on the bars 86 by a clamping bar 104, which is connected with the bar 103 by a screw 105. The pivoted stop and guide plate 101 is adjustably connected with the cross bar 103 by a slotted arm or bracket 106 attached to said plate, and a thumb screw 107 passing through the slot in said arm or bracket and threaded in the cross bar, so that the inclination of the stop and guide plate can be varied according to the shape, nature and condition of the loaves to be wrapped.

15. Wrapper supporting plates 108 and 109 are mounted on the arch 101 and a similar arch 110, attached to the bars 86 on opposite sides of the path of the plunger and below and parallel with the side folders and guides 1 and 2. The plate 109 is preferably formed on its inner side, as shown in Figs. 1 and 6, with a downwardly extending and outwardly curved or inclined flange 111, for properly directing a loaf carried by the plunger between the side folders and guides. These wrapper supporting plates are adjustable lengthwise of the side folders and guides and are secured, as shown in Fig. 3, to the arches 101 and 110 by screws passing downwardly from the plates through slots in the arches and provided with wing nuts 112, and with springs between the arches and the nuts.

For severing the wrapping paper into wrappers of the required length, the machine is provided on one side transversely to the side folders and guides 1 and 2, with a cutter consisting of a bar 113, to which a relatively stationary or fixed blade 114 is adjustably fastened, and of a bar 115, pivoted adjacent to one end to the bar 113 and provided with a blade 116, arranged to operate with the blade 114 in the manner of shears, as shown in Figs. 1 and 6. The bar 113 is formed or provided, as shown in Figs. 1, 2 and 6, with transverse racks 117, guided by transverse ways 118 on the frame. The cutter is adjusted bodily toward and from the path of the plunger 4 to vary the length 50 of the wrappers according to different lengths of loaves, by means of a longitudinal shaft 119, provided with pinions 120 meshing with the rack 117. The shaft 119 is provided at one end with a crank arm 121, having a handle and locking pin 122, working with an index plate 123, as shown in Figs. 1, 2 and 5. For operating the movable blade 116 of the cutter, the pivoted bar 115 is provided at its outer end with a curved 60 arm 124 in the path of a projection 125 on one of the cams 55, as shown in Figs. 1 and 5. The arm 124 is extended outwardly beyond the cam to provide a handle for the manual operation of the cutter.

65. The wrapper supporting plates 108 and

109 are connected at one end, as shown in Figs. 1, 3 and 6, with a rod 126, which is connected at the ends by brackets 127 with the cutter bar 113, so that said plates are adjustable with the cutter lengthwise of the side folders and guides, and the adjustment of the plate 108 transversely to said folders and lengthwise of the cutter is permitted.

For feeding wrapping paper from a roll to the folding mechanism, the machine is provided on one side, as shown in Figs. 2, 4, 5 and 6, with a pair of feed rollers 128 and 129, which operate intermittently on the paper, and with a pair of constantly operating slack rollers 130 and 131 for drawing the paper from the roll preliminarily to its intermittent advance by the feed rollers. The roller 129 is mounted above the roller 128 in arms 132 on a rocker shaft 133, and is movable vertically into and out of operative position relative to the roller 128, which is constantly rotated when the machine is in operation. The shaft 133 is provided at one end with an arm 134, and is rocked to properly time the feed of the wrapping paper by a cam 135 mounted on the shaft 32 and working with a wiper 136 with which the arm 134 is provided, and which is adjustable in said arm parallel with the shaft 133 by means of a nut 137. When the wiper, which rides on the periphery of the cam, drops into the recess 138, the roller 129 descends into operative position, carrying the paper against the driven roller 128. By the adjustment of the wiper 136 lengthwise in the arm 134, it is caused to drop sooner or later into the recess 138, thus causing the feed rollers to act sooner or later and advance the paper more or less according to the length of the loaves to be wrapped, the length of the wrappers being determined by the adjustment of the cutter which severs the paper, as hereinbefore explained, and by the adjustment of the wiper so that they will project to the same extent over both ends of the loaves. A roll of paper from which the wrappers are made, is mounted on a reel below and parallel with the feed roller 128 and above and parallel with the slack rollers 130 and 131. The reel consists of a shaft 139, removably mounted in brackets 140 on the frame, and provided with conical collars 141, which are removable from and adjustable lengthwise on said shaft for mounting, centering and holding the roll in place thereon. The slack roller 130, having bearings in the brackets 140, is made removable so that a roller of different size, according to the length of the wrappers required, may be easily substituted. It is driven by a short shaft 142, with which it is detachably coupled, and which is provided with a sprocket wheel 143 connected by a link or chain belt, as indicated by dotted lines in Figs. 4 and 5, with a sprocket wheel 144 on

the shaft of the feed roller 128. The journals of the upper roller 131, which rests upon and presses the paper against the lower driven roller 130, are guided in vertically elongated openings 145 in the brackets 140, the upper ends of these openings being offset for holding the roller temporarily in an elevated position to facilitate changing the lower roller for one of a different size, and 10 for passing the end of a new roll of paper around the roller 130 into place between the feed rollers 128 and 129.

From the roller 130 the paper is directed upwardly over an inclined guide plate 146 between the feed rollers 128 and 129. The upper edge of this plate is rolled around or otherwise fastened to a rod 147, carried by brackets on the machine frame parallel with the feed rollers. The rod 147 is fastened and 20 held against turning in its supporting brackets by one or more set screws 148, by means of which the guide plate 146 may be adjusted angularly and set at any desired inclination. The plate 146 is provided with 25 end gages 149, which are secured thereto by clamping plates 150 and thumb screws 151, passing through longitudinal slots in the guide plate, so that either of the gages may be adjusted lengthwise of the guide plate 30 for directing paper of different widths in proper position to the folding mechanism.

From the feed rollers 128 and 129 the wrapping paper is guided between the blades 114 and 116 of the cutter and upon the supports 108 and 109 by a plate 152 fastened at the ends to the cutter bar 113 a short distance below and parallel with the blade 114, and by a plate 153 fastened at its ends to the frame of the machine and overlapping at 40 its inner edge the outer edge of the plate 152, as shown in Figs. 1 and 6.

For driving the machine, an electric motor 154 is shown, a pulley 155 on the motor shaft being connected by a belt with a pulley 156 on the shaft of the feed roller 128, which in the present case is the main driving shaft of the machine, and is connected with the cam shaft 32 by bevel gears 157 and 158. The gear 158 may be formed as shown, with 50 the cam 135.

A number of loaves placed side by side on the feed belt 82 being required to afford sufficient frictional contact with the belt to push a loaf from the shelf 34 upon the plunger 4, provision is made for automatically stopping the machine when less than the requisite number of loaves to insure proper feeding thereof to the plunger, are on the feed belt 82, as shown in Figs. 1, 2 and 4.

A rocker shaft 159, supported over and transversely to the belt 82 by standards fastened to and extending upwardly from the bars 86, has a gravity arm 160 formed 65 or provided with a shoe 161, which is

adapted to ride upon and over the tops of the loaves when they are fed side by side in an unbroken row to the plunger 4. At one end the shaft 159 is provided with an arm 162, adapted to open an electric switch 163, controlling the supply of current to the motor 154 whenever the shoe 161 is left unsupported by a loaf of bread. 70

The loaves of bread or articles to be wrapped are designated by the numeral 164, 75 while the wrappers or wrapped packages are designated by the numeral 165.

In the operation of the machine for wrapping bread, the proper adjustments for wrapping loaves of a given size having been 80 made and a roll of paper of the proper width for wrapping such loaves having been placed in the machine on the reel shaft 139 and the end of the paper carried downwardly between the slack rollers 130 and 131, thence upwardly over the guide plate 146 between the feed rollers 128 and 129 and over guide plates 152 and 153, into position on the wrapper supports 108 and 109, the operator places the loaves to be wrapped 90

side by side on the feed belt 82. The constantly traveling belt 82 brings the loaves closely together side by side, and pushes them forward across the shelf 34 upon the plunger 4, where the front loaf is arrested 95 in proper position by the stop and guide plate 101. As the loaves are advanced they are brought into alignment and into proper position lengthwise by the converging guides 98, for delivery to the pusher. With each 100 revolution of the shaft 32, the plunger with a loaf thereon is carried upwardly between the folders and guides and returned to its initial position to receive another loaf, by the eccentric 31. In the upward movement 105 of the plunger with a loaf thereon, a wrapper is taken from the supports 108 and 109 and carried upwardly between the side folders and guides 1 and 2, which fold the wrapper lengthwise upon the top and sides of the 110 loaf, as shown in Figs. 7 and 8, the outwardly yielding sections 12 of the folders evenly distributing the pressure against the sides of the loaf and the pull on the sides of the wrapper. 115

As the top of the loaf is moved upwardly into contact with the inwardly projecting ends of the end folders 3, said folders are turned from the position in which they are shown in Fig. 7 to that in which they are 120 shown in Fig. 9, thereby laying broad end folds with underlying triangular corner folds against the ends of the loaf, as shown in Figs. 9 and 10, the downwardly turned sides of the wrapper being confined during 125 this operation, as shown in Figs. 7 and 8, by the upper stationary sections of the side folders and guides 1 and 2, so that as the broad overlying end folds are pressed by the end folders against the ends of the loaf, 130

the surplus paper is turned inwardly and formed into underlying triangular corner folds, as indicated by dotted lines on Fig. 10. The loaf being carried by the plunger 5 upwardly between the pusher 7, the gate 65, and the end guides 80, which exert sufficient pressure thereon to hold it in place and at the same time confine the wrapper against the sides and ends of the loaf, as the plunger 10 descends, the tuckers 6 are moved inward by the joint action of the levers 53 and cams 55, and fold the depending edges or flaps of the previously formed end folds underneath and against the bottom of the 15 loaf, as shown by Figs. 11 and 13. As the end tuckers 6 are withdrawn, the side tucker 5 is advanced by the joint action of the lever 47 and cam 50, and folds the depending edge or flap of the side fold next to the 20 pusher 7 underneath and against the bottom of the loaf and the infolded end flaps, as shown by Figs. 12 and 13. The gate 65 is then lifted by the cam 73 and the lever 71 connected with the swinging frame 66, 25 and the pusher 7 is advanced by the cam 60 and the lever 58, thereby thrusting the loaf between the end guides 80 upon the plate 63. The side tucker 5 and the pusher 7 are withdrawn to their initial positions, as 30 shown in Fig. 1, by the springs 51 and 61. As the loaf is thrust by the pusher 7 upon the plate 63, the depending edge or flap of the side fold next to said plate is turned back by the edge of said plate against the 35 bottom of the loaf over the bottom folds previously formed by the end and side tuckers, thereby closing the package and lapping all the edges of the wrapper on the bottom of the loaf, as shown by Fig. 13.

40 After the wrapped loaf has been thus deposited by the pusher on the plate 63, which is kept at the required temperature by the heater 64, the gate 65 is returned to its original position and the presser plate 75 45 is moved downward against the top of the loaf, as shown in Fig. 1, by the retracting spring 74. The plate 75 yieldingly pressing and holding the bottom of the package against the hot plate 63, causes the lapped 50 edges or folds of the paraffined or waxed wrapper on the bottom of the loaf to stick together, thereby effectively sealing the package.

The presser plate 75 is preferably made, 55 as shown in Fig. 1, of sufficient width to act at the same time on two single loaves, or a double loaf.

The wrapped and sealed loaves are thrust by the repeated action of the pusher 7, 60 from the hot plate 63, upon the discharge belt 87, from which they are removed by the operator.

The bread to be wrapped is ordinarily taken by the operator from a truck or portable rack such as are used in bakeries, on

which it is placed as it comes from the oven and upon which the wrapped loaves are replaced as they are taken from the machine.

The feed and discharge conveyors being located one below the other and near each other, enable a single operator to easily supply the machine with the bread to be wrapped and to remove the wrapped loaves therefrom.

With the initial upward movement of 75 the plunger 4, the gate 35 is moved upwardly and the guard 40 is moved downwardly, so as to prevent the displacement of the loaf on the shelf 34 by the upward movement of the loaf on the plunger, the 80 row of loaves on the feed belt 82 being held back by the gate and by the loaf on the shelf till the plunger and the gate return to their initial positions.

As the plunger 4 passes below the wrapper supports 108 and 109 on its return to its initial position to receive another loaf, the wiper 136 drops into the recess 138 of cam 135, thereby permitting the upper feed roller 129 to descend and carry the paper 90 into contact with the rotating roller 128. A sufficient length of paper for a wrapper is thus advanced into proper position on the supports 108 and 109, whereupon the high 95 part of the cam 135 at the end of the recess 138, engaging with the wiper 136 as shown in Fig. 4, lifts the roller 129 away from the roller 128, arresting the further advance of the paper. The cam projection 125 then engages with the arm 124 of the 100 pivoted cutter bar 115, swinging the blade 116 upwardly across the edge of the stationary blade 114 and cutting a wrapper of the length required from the strip of paper held between the stationary blade 114 and 105 the guide plate 152 below it.

While the feed rollers 128 and 129 are separated and inoperative, the rollers 130 and 131 continue to operate, drawing paper from the roll above them on the reel 139, so 110 that enough paper is unwound from the roll for a wrapper before it is advanced by the feed rollers 128 and 129 to the folding mechanism.

When the machine is run at a slow or moderate speed, and paper of sufficient strength is used, the rollers 130 and 131 may be dispensed with, and the paper fed directly from the roll to the folding mechanism by the rollers 128 and 129.

Other mechanism or devices may be used for feeding wrappers to the machine either from a stack or a roll.

If wider loaves are to be wrapped, the machine is adjusted therefor as follows:

The side folder and guide 2 is moved the required distance from the stationary folder and guide 1, the screws 9 being loosened to permit them to be shifted in the slots 10, and then tightened after the adjustment 130

has been properly made. The plates 14 of the end folders are replaced by wider plates corresponding with the increased distance between the side folders and guides 1 and 2.

5 The back stop plate and guide 101 with the wrapper support 108, is moved a corresponding distance away from the shelf 34 and wrapper support 109, the screw 105 being loosened to permit the cross bar 103 with the arch 102 to be shifted on and lengthwise of the bars 86. The stop screws 52 and 62 are set to permit a further outward movement of the side tucker 5 and pusher 7, and to arrest them in their initial 10 or normal positions in proper relation to the side folder 1 and guide 2. If the increase in the width of the loaves is considerable, it may be necessary or desirable to provide the machine with a wider plunger 4, and with 15 wider end tuckers 6, and it may be necessary or desirable to increase the speed of the feed belt 85 by shifting the link or chain belt 92 to a part or section of the cone sprocket wheel 93 of smaller diameter. For 20 wider loaves, wider wrapping paper is used, and one or both of the conical collars 141 on the reel shaft 139, and one or both of the end gages 149 on the guide plate 146, must be correspondingly adjusted.

30 If longer loaves are to be wrapped, the machine is adjusted therefor as follows:

The inner ends of the guides 98 are set farther apart by the adjusting screw 100. The end folders 3 with the end guides 80 35 are set correspondingly farther apart by the adjusting screw 26. A wider pusher plate 7, corresponding with the increased distance between the end guides 80, is attached to the head 56. The wiper 136 is 40 set toward the arm 134, so that the feed roller 129 will drop into operative position sooner and continue in operation longer, to increase the length of the wrapper. The cutter is moved away from the path of the 45 plunger by means of the crank arm 121 and set in such a position that the wrapper will project the same distance from each end of the loaf. When slack rollers are used, a roller of larger diameter is substituted for 50 the lower roller 130 to increase the slack in the paper preparatory to the operation thereon of the feed rollers, according to the increased length of the wrappers.

For wrapping loaves of greater or less 55 depth or height, the only adjustment required is to raise or lower the presser plate 75 which is effected by screwing the sleeves 77 up or down in the frame 66.

Various changes in details of construction 60 and arrangement of parts of the machine may be made without departing from the principle of the invention as defined in the following claims.

I claim:

65 1. In a wrapping machine the combina-

tion of opposing parallel side folders and guides, a reciprocating plunger movable between said folders and guides, and end folders pivoted between and transversely to said side folders and guides, normally projecting at their inner ends into the path of the article to be wrapped and adapted as the article is thrust by the plunger between them and the side folders and guides to simultaneously form two triangular in-folds with an overlying end fold of the wrapper on each end of the article, the side folders and guides extending at the ends beyond the pivots of the end folders.

2. In a wrapping machine the combination of opposing parallel side folders and guides, a reciprocating plunger movable between said folders and guides, end folders pivoted between and transversely to said side folders and guides, and normally projecting at their inner ends into the path of the article to be wrapped, the side folders and guides extending at the ends beyond the pivots of the end folders, means for feeding the articles to be wrapped to the plunger one at a time, and means for feeding wrappers between the articles on the plunger and the side folders and guides.

3. In a wrapping machine the combination of opposing parallel side folders and guides, a reciprocating plunger movable between said folders and guides, end folders pivoted between and transversely to said side folders and guides and normally projecting at their inner ends into the path of an article to be wrapped as it is thrust by the plunger with a wrapper between said side folders and guides, the side folders and guides extending at their ends beyond the pivots of the end folders; means for feeding wrappers between the plunger in its initial position and the side folders and guides, a conveyer arranged transversely to the path of the plunger and adapted to feed the articles to be wrapped thereto, a gate 100 movable adjacent to the plunger across the path of the articles fed thereto, and means for moving said gate into and out of operative position as the plunger is advanced from and returned to its initial position, 105 the plunger in its advance being movable independently of and beyond the gate.

4. In a wrapping machine the combination of opposing parallel side folders and guides, a reciprocating plunger movable between 120 said folders and guides, end folders pivoted between and transversely to said side folders and guides and normally projecting at their inner ends into the path of an article to be wrapped as it is thrust by the plunger with a wrapper between said side folders and guides, the side folders and guides extending at the ends beyond the pivots of the end folders; means for feeding wrappers between the plunger in its initial position and 125 130

- the side folders and guides, a conveyer arranged transversely to the path of the plunger and adapted to feed the articles to be wrapped thereto, a guard movable toward 5 and from the conveyer opposite the article next to that on the plunger, and means for moving said guard into operative position toward the conveyer when the plunger is advanced from its initial position.
- 10 5. In a wrapping machine the combination with folding mechanism comprising a reciprocating plunger, of feeding mechanism comprising an endless traveling belt movable on the upper side, which is located approximately in the plane of the plunger in 15 its initial position toward and transversely to the path of the plunger, and longitudinal guides located above and adjacent to each side of the belt and converging toward the path of the plunger, said guides being adjustable toward and from each other at their converging ends.
- 20 6. In a wrapping machine the combination with wrapping mechanism for completely wrapping an article, of feed and discharge conduits located on the same side of the machine in different planes, one above the other, means for moving articles to be wrapped in the feed conduit toward the 25 wrapping mechanism, means for transferring the articles from the feed conduit to the wrapping mechanism, means for delivering the completely wrapped articles from the wrapping mechanism into the discharge conduit, and gates to the feed and the discharge conduits at the ends nearest the path of travel of the plunger.
- 30 7. In a wrapping machine the combination of feeding and discharge conveyers and 40 mechanism for completely wrapping an article, said mechanism including a vertically reciprocating plunger and said conveyers being arranged at the same side of said mechanism, one in a lower plane than the other 45 and transversely to the path of the plunger at the limits of its movement and movable respectively toward and from the path of the plunger, the discharge conveyer receiving the completely wrapped articles 50 from said mechanism, and gates at the ends of the conveyers nearest the path of travel of the plunger.
- 55 8. In a wrapping machine the combination with wrapping mechanism comprising vertically disposed parallel side folders and guides and a reciprocating plunger movable between said folders and guides, endless traveling feed and discharge conveyer belts arranged respectively with their upper sides 60 approximately in the planes of the plunger at the limits of its movement, means for driving said belts respectively toward and from the path of the plunger, feed and discharge gates movable into and out of the 65 paths of the articles as they are fed to and delivered from the path of the plunger, means for moving said gates into and out of operative position at the proper times, and a reciprocating pusher for transferring the wrapped articles from the path of the 70 plunger upon the discharge belt.
- 75 9. In a wrapping machine the combination with wrapping mechanism comprising parallel side folders and guides and a reciprocating plunger movable between said folders and guides, of a heating plate arranged at one side of and transversely to the path of the plunger at its delivery end, means for heating said plate, means for transferring wrapped articles from the plunger to said 80 plate, and a reciprocating presser movable toward and from said plate and adapted to press the wrapped articles against the same as they are delivered thereon.
- 85 10. In a wrapping machine the combination with wrapping mechanism comprising parallel side folders and guides and a reciprocating plunger movable between said folders and guides, of a heating plate arranged at one side of and transversely to the path 90 of the plunger at its delivery end, means for heating said plate, a reciprocating pusher movable across the path of the plunger toward and from the heating plate, and a yielding reciprocating presser movable 95 toward and from said plate transversely to the movement of the pusher.
- 100 11. In a wrapping machine the combination with wrapping mechanism comprising parallel folders and guides and a reciprocating plunger movable between said folders and guides, of a reciprocating discharge pusher movable transversely to said folders and guides across the space between them, and a reciprocating gate movable transversely to the movement of the pusher into and out of the path of the wrapped articles as they are removed from the path of the plunger by the pusher, said pusher and gate standing in their normal positions approximately in the planes of said folders and guides and forming continuations thereof.
- 105 12. In a wrapping machine the combination of parallel side folders and guides, a reciprocating plunger movable between said 115 folders and guides, end folders pivoted between and transversely to the side folders and guides and normally projecting at their inner ends into the path of the article to be wrapped on the plunger, the side folders and guides extending at the ends beyond the pivots of the end folders, reciprocating end tuckers movable toward and from each other lengthwise of the side folders and guides and transversely to the path of the plunger, a reciprocating side tucker movable crosswise of the side folders and guides and transversely to the path of the plunger and means for operating said tuckers in proper sequence.
- 110 120 125 130

13. In a wrapping machine the combination of parallel side folders and guides, a reciprocating plunger movable between said folders and guides, end folders pivoted between and transversely to the side folders and guides and tending to project at their inner ends into the path of an article on the plunger, end guides located above and transversely to the side folders and guides, a reciprocating pusher movable between the end guides transversely to the side folders and guides, a gate movable transversely to the movement of the pusher into and out of its path, said pusher and gate standing in their normal positions approximately in the planes of the side folders and guides and forming continuations thereof, end tuckers movable toward and from each other lengthwise of the side folders and guides and between them and the end guides, a reciprocating side tucker movable parallel with and close to the plane of the end tuckers transversely to and between the pusher and one side folder and guide, and means for operating said tuckers, gate and pusher in proper sequence. 70
14. In a wrapping machine the combination of a vertically reciprocating plunger, feed and discharge conveyers arranged on the same side of the machine and movable in opposite directions toward and from and transversely to the path of the plunger, one conveyer being located in a plane above that of the other, folding mechanism coöperating with the plunger to completely fold the wrappers on packages as they are transferred from the feed to the discharge conveyer, and gates at the ends of the conveyers nearest the path of travel of the plunger. 80
15. In a wrapping machine the combination of vertically disposed parallel side folders, a reciprocating plunger movable between them, end folders pivoted between and transversely to the side folders and on opposite sides of the path of the plunger and counterweighted to turn and project normally inward into and transversely to the path of an article on the plunger, the side folders extending at the ends beyond the pivots of the end folders, and stops for limiting the movement of the end folders. 90
16. In a wrapping machine the combination of opposing parallel side folders, one of which is adjustable toward and from the other, a reciprocating plunger movable between them, and end folders pivoted between and transversely to the side folders and on opposite sides of the path of the plunger and each provided with a detachable folding plate, whereby the end folders may be provided with plates for wrapping articles of different sizes, the side folders extending at the ends beyond the pivots of the end folders. 100
17. In a wrapping machine the combination of opposing parallel side folders, a re- ciprocating plunger movable between them, and end folders pivoted between and transversely to the side folders and guides, a reciprocating plunger movable between them, heads adjustable toward and from each other lengthwise of the side folders, rods secured to said heads and passing through the slots in the side folders, end folders pivotally and slidably mounted on said rods between the side folders and tending to tip inwardly at their upper ends into the path of an article on the plunger, and a right and left adjusting screw connecting said heads. 110
18. In a wrapping machine the combination of opposing parallel longitudinally slotted side folders, a reciprocating plunger movable between them, heads adjustable toward and from each other lengthwise and along the outer side of one of the side folders, rods secured to said heads and passing through the slots in the side folders, end folders pivotally and slidably mounted on said rods between the side folders and tending to tip inwardly at their upper ends into the path of an article on the plunger, and a right and left adjusting screw connecting said heads. 120
19. In a wrapping machine the combination of vertically disposed longitudinally slotted side folders, a reciprocating plunger movable between them, heads adjustable toward and from each other lengthwise of the side folders, rods secured to said heads and passing through the slots in the side folders transversely thereto, end folders pivotally mounted on said rods between the side folders and tending to tip inwardly at their upper ends into the path of an article on the plunger, parallel end guides located above and transversely to the side folders and connected and adjustable with said heads and end folders, and means for adjusting said heads toward and from each other. 130
20. In a wrapping machine the combination with folding mechanism comprising parallel side folders, end folders pivoted between and transversely to the side folders and adjustable lengthwise thereof, a reciprocating plunger movable between the opposing side and end folders, a feed belt located on the upper side approximately in the plane of the plunger in its initial position, longitudinal guides located above and on opposite sides of the feed belt and converging toward the path of the plunger, and means for adjusting the converging ends of said guides toward and from each other. 140
21. In a wrapping machine the combination of vertically disposed opposing parallel side folders, a reciprocating plunger movable between said folders, end guides located above and transversely to the side folders and adjustable lengthwise thereof, and a reciprocating pusher movable between and parallel with the end guides across the space between the side folders and provided with a detachable plate corresponding in length with the space between the end guides. 150
22. In a wrapping machine the combina- 160

tion of folding mechanism comprising vertically disposed parallel side folders, one of which is adjustable toward and from the other for wrapping articles of different widths, a reciprocating plunger movable between said folders, a reciprocating pusher located above and movable transversely to the side folders, a cam for advancing said pusher, a spring for retracting the pusher, and an adjustable stop for limiting the backward movement of the pusher approximately in the plane of one of the side folders.

23. In a wrapping machine the combination of folding mechanism comprising vertically disposed parallel side folders, one of which is adjustable toward and from the other, a reciprocating plunger movable between said folders, means for confining a wrapped article above said folders, a reciprocating side tucker movable transversely to the side folders between them and said confining means, a cam for advancing the tucker, a spring for retracting the tucker, and an adjustable stop for limiting the backward movement of the tucker approximately in line with one of the side folders.

24. In a wrapping machine the combination with folding mechanism comprising side and end folders, a vertically reciprocating plunger movable between said folders, means for feeding a wrapper between the folders and the plunger when the latter is in its initial position, a heating plate located adjacent to the top and transversely to one of the side folders, a reciprocating pusher adapted to transfer wrapped articles from the path of the plunger to said heating plate, a vertically adjustable and yielding presser movable toward and from said plate, and means for operating said plunger, pusher and presser in proper sequence.

25. In a wrapping machine the combination of vertically disposed side folders and guides having outwardly yielding sections hinged at their upper edges to the lower edges of said folders and guides, and a reciprocating plunger movable between said folders and guides.

26. In a wrapping machine the combination with folding mechanism comprising vertically disposed parallel side folders and guides and a reciprocating plunger movable between them, of a horizontally disposed belt adapted to feed the articles to be wrapped upon the plunger in its initial position below said folders and guides, a back stop and guide pivotally supported below and parallel with the side folder and guide between it and the plunger in its initial position on the opposite side from the feed belt, and means for adjusting the lower side of said back stop and guide toward and from the path of the plunger.

27. In a wrapping machine the combina-

tion of vertically disposed side folders and guides, one of which is horizontally adjustable toward and from the other, a reciprocating plunger movable between said folders and guides, a horizontally disposed conveyer for feeding the articles to be wrapped upon the plunger in its initial position below said folders and guides, and a horizontally and angularly adjustable back stop and guide located below and parallel with the side folder and guide on the opposite side of the path of the plunger from said conveyer.

28. In a wrapping machine the combination with folding mechanism comprising vertically disposed side folders and guides and a reciprocating plunger movable between them, of a horizontally disposed conveyer for feeding the articles to be wrapped to the plunger in its initial position below said folders and guides, a gate movable vertically into and out of the path of the articles to the plunger adapted to be moved by the descent of the plunger into inoperative position, a spring connected with the gate and adapted to lift it into operative position with the initial upward movement of the plunger, and a stop for limiting the upward movement of the gate.

29. In a wrapping machine the combination with folding mechanism comprising vertically disposed folders and guides and a reciprocating plunger movable between them, of a shelf located approximately in the plane of the plunger in its initial position below said folders and guides, a conveyer adapted to feed the articles to be wrapped across said shelf to the plunger in its initial position, a vertically movable gate between the shelf and the path of the plunger adapted to be moved by the plunger in its descent into inoperative position below the shelf, means tending to lift the gate into operative position with the ascent of the plunger, a guard located above and movable toward and from said shelf, a spring connected with and tending to move the guard downward into operative position, and a lever connected with said guard and adapted by engagement with a part of the gate to lift the guard into inoperative position when the gate descends into inoperative position.

30. In a wrapping machine the combination with folding mechanism comprising opposing parallel side folders, end folders adjustable toward and from each other between the side folders, and a reciprocating plunger movable between said folders, of wrapper supports located below and parallel with the side folders on opposite sides of the path of the plunger and adjustable lengthwise of said side folders, and means for feeding wrappers into proper position on said supports.

31. In a wrapping machine the combination with folding mechanism comprising opposing parallel side folders, end folders adjustable toward and from each other between the side folders, and a reciprocating plunger movable between said folders, of means for feeding wrapping paper into proper position below said folders and above the plunger in its initial position, and a cutter for severing the paper arranged transversely to the side folders and adjustable lengthwise thereof. 65
32. In a wrapping machine the combination with folding mechanism comprising opposing parallel side folders, end folders adjustable toward and from each other between the side folders, and a reciprocating plunger movable between said folders, of wrapper supports located below and parallel with the side folders on opposite sides of the path of the plunger and adjustable lengthwise of the side folders, and means for feeding wrappers into position on said supports above the plunger in its initial position. 70
33. In a wrapping machine the combination with folding mechanism comprising parallel side folders, end folders adjustable toward and from each other between and lengthwise of the side folders, and a reciprocating plunger movable up and down between said folders, of wrapper supports located below and parallel with the side folders on opposite sides of the path of the plunger and adjustable lengthwise thereof, means for feeding wrappers into position on said supports above the plunger in its initial position, and a cutter for severing the paper into the required lengths arranged transversely to the side folders and connected and adjustable with the wrapper supports. 75
34. In a wrapping machine the combination with folding mechanism comprising side folders, end folders adjustable toward and from each other and a reciprocating plunger movable between said folders, of means for feeding wrapping paper into proper position between said folders and the plunger in its initial position, a cutter for severing the paper into the required lengths adjustable toward and from the path of the plunger, and means for operating the cutter. 80
35. In a wrapping machine the combination with folding mechanism comprising side folders, end folders adjustable toward and from each other lengthwise of the side folders, and a reciprocating plunger movable between said folders, of means for feeding wrapping paper into position between said folders and the plunger in its initial position, a cutter for severing the paper into the required length, adjustable toward and from the path of the plunger and provided with racks, a shaft provided with pinions meshing with said racks, means for turning said shaft, and means for locking it with the cutter in different positions. 85
36. In a wrapping machine the combination with folding mechanism comprising side folders, end folders adjustable toward and from each other lengthwise of the side folders and a reciprocating plunger movable between said folders, of means for feeding wrapping paper between said plunger in its initial position and the folders, a cutter for severing the paper into wrappers of the required length adjustable lengthwise of the side folders toward and from the path of the plunger and provided with racks parallel with the side folders, a shaft provided with pinions meshing with said racks, means for turning said shaft, means for locking it in different positions, wrapper supports located below the folders on opposite sides of the path of the plunger and connected and adjustable with the cutter lengthwise of the side folders. 90
37. In a wrapping machine the combination with folding mechanism comprising folders adjustable for packages of different sizes and a reciprocating plunger movable between the folders, of paper feeding mechanism comprising a pair of rollers one of which is movable toward and from the other into and out of operative position, a rocker shaft having an arm provided with an adjustable wiper, a cam adapted to coöperate with said wiper to shift the movable roller at the proper time into operative position, and means for rotating one of said rollers. 95
38. In a wrapping machine the combination with folding mechanism comprising folders adjustable for packages of different sizes and a reciprocating plunger movable between said folders, of paper feeding mechanism comprising a pair of rollers one of which is movable toward and from the other into and out of operative position, a rocker shaft carrying the movable roller and provided with an arm, a cam coöperating with said arm to shift the movable roller into operative position, one of said coöperating parts being adjustable to vary the time of shifting the movable roller into operative position according to the adjustment of the folders, and means for rotating one of said rollers. 100
39. In a wrapping machine the combination with wrapper folding mechanism comprising folders adjustable toward and from each other for packages of different sizes and a reciprocating plunger movable between said folders, of wrapper supports located on opposite sides of the path of the plunger adjacent to the folders, a pair of feed rollers one of which is movable toward and from the other into and out of operative 105
40. In a wrapping machine the combination with folding mechanism comprising side folders, end folders adjustable toward and from each other lengthwise of the side folders, and a reciprocating plunger movable between said folders, of means for feeding wrapping paper into position between said folders and the plunger in its initial position, a cutter for severing the paper into the required lengths adjustable toward and from the path of the plunger and provided with racks, a shaft provided with pinions meshing with said racks, means for turning said shaft, and means for locking it with the cutter in different positions. 110
41. In a wrapping machine the combination with folding mechanism comprising side folders, end folders adjustable toward and from each other lengthwise of the side folders, and a reciprocating plunger movable between said folders, of means for feeding wrapping paper into position between said folders and the plunger in its initial position, a cutter for severing the paper into the required lengths adjustable toward and from the path of the plunger and provided with racks, a shaft provided with pinions meshing with said racks, means for turning said shaft, and means for locking it with the cutter in different positions. 115
42. In a wrapping machine the combination with folding mechanism comprising side folders, end folders adjustable toward and from each other lengthwise of the side folders, and a reciprocating plunger movable between said folders, of means for feeding wrapping paper into position between said folders and the plunger in its initial position, a cutter for severing the paper into the required lengths adjustable toward and from the path of the plunger and provided with racks, a shaft provided with pinions meshing with said racks, means for turning said shaft, and means for locking it with the cutter in different positions. 120
43. In a wrapping machine the combination with folding mechanism comprising side folders, end folders adjustable toward and from each other lengthwise of the side folders, and a reciprocating plunger movable between said folders, of means for feeding wrapping paper into position between said folders and the plunger in its initial position, a cutter for severing the paper into the required lengths adjustable toward and from the path of the plunger and provided with racks, a shaft provided with pinions meshing with said racks, means for turning said shaft, and means for locking it with the cutter in different positions. 125

position for advancing the paper into proper position on said supports, means for varying the time of movement of one of said rollers toward the other, a cutter located between the feed rollers and folding mechanism and adjustable toward and from the path of the plunger for severing the paper into wrappers of the required length, a reel for holding a roll of paper, a pair of slack 10 rollers for drawing the paper from the roll preparatory to its intermittent advance by the feed rollers to the folding mechanism, the upper slack roller being movable vertically and resting normally on the lower 15 roller which is removable for substituting therefor a roller of different size, and means for rotating said slack rollers.

40. In a wrapping machine the combination of wrapper folding mechanism comprising folders adjustable toward and from each other and a vertically reciprocating plunger movable between said folders, of wrapper supports located on opposite sides of the path of the plunger adjacent to the 20 folders, feed rollers adapted to intermittently advance the wrapping paper into position on said supports, a cutter located between the feed rollers and folding mechanism and adjustable toward and from the path of the plunger, a paper guide connected and adjustable with the cutter, and a stationary paper guide overlapping the adjustable paper guide and bridging the space 25 between it and said rollers.

35 41. In a wrapping machine the combina-

tion with folding mechanism comprising side folders adjustable toward and from each other, of intermittently operating wrapper feeding rollers, a reel for holding a roll of paper, constantly operating slack 40 rollers for drawing the paper from the roll preparatory to its advance by the feed rollers, and a guide plate located in the path of the paper from the slack rollers to the feed rollers and provided with end gages 45 adjustable toward and from each other for directing paper of different widths in proper position to the feed rollers and the folding mechanism.

42. In a wrapping machine the combination of means for folding a quadrangular wrapper lengthwise over the top and sides of a package, means for simultaneously laying end folds with underlying inturned triangular corner folds in the wrapper over 50 the ends of the package from top to bottom, means for folding the edges of the end and inturned corner folds inwardly on the bottom of the package, and means for folding the edges of the side folds inwardly one 55 over the other and both of them over the edges of the inturned end folds on the bottom of the package.

In witness whereof I hereto affix my signature in presence of two witnesses.

PETER F. MURPHY.
